UNITED STATES PATENT OFFICE.

JOHN KNECHT, OF BLUFFTON, INDIANA.

OILER.

SPECIFICATION forming part of Letters Patent No. 787,846, dated April 18, 1905.

Application filed December 1, 1904. Serial No. 234,983.

To all whom it may concern:

Be it known that I, JOHN KNECHT, a citizen of the United States, and a resident of Bluffton, Indiana, have invented certain new and useful Improvements in Oilers, of which the following is a specification, containing a full, clear, and exact description, reference being had to the accompanying drawings, forming a part hereof.

My invention relates to improvements in oilers; and it consists of the novel features herein shown, described, and claimed.

In the drawings, Figure 1 is a perspective showing my improved oiler applied to the gearing of a windmill, the foundation of the tower being broken away to economize space and the wind-fans being omitted. Fig. 2 is an enlarged elevation of the oiler removed from the windmill-gearing, the view being taken looking in the direction indicated by the arrow 2 in Fig. 1. Fig. 3 is a horizontal section on the line 3-3 of Fig. 2 and looking in the direction indicated by the arrow, the supporting-brackets being omitted. Fig. 4 is a sectional elevation on a plane parallel with Fig. 1, upon an enlarged scale, of the oiler removed from the windmill-gearing, the view being taken at right angles to Fig. 2.

Referring to the drawings in detail, the supporting-post 5 is adapted for attachment to the frame of the windmill-gearing or to any other device to which the oiler is to be applied, brackets 6 and 7 extending upwardly from the post. An oil-distributing chamber 8 is formed in the upper end of the post 5, and oil-feeding tubes 9 lead downwardly from the chamber. A channel guide-arm 10 leads upwardly from the oil-distributing chamber 8, the channel of the arm communicating with the chamber and there being a stop 11 crossing the upper end of the channel. A split clamping-ring 12 has trunnions 13 and 14, mounted in the upper ends of the brackets 6 and 7. The oil-can 15 is mounted in the ring 12, the body of the oil-can being cylindrical in form and having a filling-nipple 16 at its upper end. The tube 17 extends upwardly from the oil-can, the filling-nipple being at one side of the top of the oil-can and the tube 17 being at the opposite side, and the upper

end of the tube 17 is closed. The measuring-tube 18 is mounted in the tube 17 and extends to the bottom of the can 15, there being an elbow-bend at the bottom of the can, so that the measuring-tube leads along the bottom of the can to the opposite side, and then a second elbow-bend leads downwardly through the bottom of the can. The lower end of the measuring-tube 18 strikes the stop 19, which extends across the upper part of the oil-distributing chamber 8 when the can is in the vertical position, as in Figs. 1 and 2, and strikes the stop 11 across the upper end of the channel in the guide-arm 10 when the can is in a horizontal position, as in Fig. 4, and the said lower end of the measuring-tube travels back and forth in the channel of the guide-arm, so that any oil which may drip from this measuring-tube at any time will be conducted to the oil-distributing chamber.

The rod 20 is attached to the ears 21 on the back side and upper end of the can 15 and to the shifting mechanism of the windmill or other machine to be lubricated, so that when the mill is thrown out of operation the can is tipped to its horizontal position, thereby allowing the oil to run from the can into the upper end of the measuring-tube 18, and so that when the parts are shifted to start the mill the can will be tipped to its vertical position, thereby allowing the oil in the measuring-tube to run into the distributing-chamber 8 and from the distributing-chamber through the oil-feeding tubes 9 to the bearings and parts to be lubricated.

It is obvious that this principle may be applied to any machine without departing from the spirit of my invention.

The object of the extension-tube 17 is to provide means for extending the receiving end of the measuring-tube upwardly, so that no oil will enter the receiving end of the measuring-tube until the oil ceases to flow from the discharge end in tilting the oil-can from its vertical to its horizontal position.

I claim—

1. In an oiler: the supporting-post 5; the brackets 6 and 7 extending upwardly from the post; there being an oil-distributing chamber 8 in the upper end of the post; the oil-feeding

2
tube 9 leading downwardly from the chamber; the channel guide-arm 10 leading upwardly from the oil-distributing chamber and the oil-can pivotally mounted between the brackets 5 and adapted to discharge into the oil-chamber when in the vertical position; the discharge end of the oil-can being in the channel-bar 10 so as to conduct the drippings to the oil-chamber.

2. In an oiler: a distributing-chamber; the 10 channel guide-arm leading upwardly from the distributing-chamber; the oil-can 15 pivotally mounted above the distributing-chamber; the measuring-tube 18 mounted in the oiler-can; said measure-tube being Z-shaped and the 15 discharge end of the measuring-tube extending into the channel-arm so that the measuring-tube will be discharged when in a vertical position.

3. In an oiler: a suitable support having an 20 oil-distributing chamber; a channel-arm lead-

ing upwardly from the oil-distributing chamber; the oil-can 15 pivotally mounted above the oil-distributing chamber; the tube 17 extending upwardly from the oil-can; the measuring-tube 18 mounted in the tube 17; and 25 extending to the bottom of the can 15; there being an elbow-bend at the bottom of the can so that the measuring-tube leads along the bottom of the can to the opposite side; and a second elbow-bend leading downwardly 30 through the bottom of the can; the lower end of said second elbow-bend being in the channel of the guide-arm; substantially as specified.

In testimony whereof I have signed my name to this specification in presence of two sub- 35 scribing witnesses.

JOHN KNECHT.

Witnesses:

W. I. EVANS,
FRED AHBAUCHER.
